Primary Examiner—Brian N Vinson*(74) Attorney, Agent, or Firm*—Whyte Hirschboeck Dudek SC**CLAIM**

The ornamental design for a trolling board storage device, as shown and described.

DESCRIPTION

FIG. 1 is a perspective view of a tolling board storage device illustrating my new design;

FIG. 2 is a front view thereof; and,

FIG. 3 is a top plan view thereof.

The broken lines shown in the figures are for illustrative environmental purposes only and form no part of the claimed design.
